UNITED STATES PATENT OFFICE.

AXEL VIKTOR JOHNSON, OF BROOKLYN, NEW YORK, ASSIGNOR TO FRED GOAT COMPANY, OF BROOKLYN, NEW YORK, A CORPORATION OF NEW YORK.

MEANS FOR PREVENTING BACKLASH IN ROUNDING AND BACKING MACHINES.

Application filed December 10, 1920. Serial No. 429,665.

To all whom it may concern:

Be it known that I, AXEL VIKTOR JOHNSON, a subject of the King of Sweden, but who have declared my intention of becoming 5 a citizen of the United States, residing at Brooklyn, county and State of New York, have made a certain new and useful Invention in Means for Preventing Backlash in Rounding and Backing Machines, of which 10 the following is a specification.

This invention relates to means employed in connection with what is known in the art as the Crawley machine for rounding and 15 backing books, periodicals, and the like, the machine which is in practical universal use for this purpose is known as the Crawley machine, which is shown and described in detail in United States Letters Patent No. 372,128, dated October 25, 1887, and issued 60 to E. Crawley. For the perfect and satisfactory operation of this machine it is important that the sweep returns quietly to its initial and exact position for new work 65 without rebound or back lash.

The object of the invention is to provide means for insuring a proper positioning of 20 the sweep jaws relative to the book fed therebetween on each forward position of the sweep.

A further object of the invention is to provide a counter-balance arrangement 25 which secures the results sought.

A further object of the invention is to provide an arrangement of the character set forth which is simple in construction, efficient in operation, and which may be 30 formed as a part of a new machine at little additional expense, or may be applied to machines already in existence, at but little additional expense.

Further objects of the invention will appear more fully hereinafter.

The invention consists substantially in the construction, combination, location, and relative arrangement of parts, all as will be more fully hereinafter set forth, as shown 40 by the accompanying drawing, and finally pointed out in the appended claims.

Referring to the drawing,—

Fig. 1 is a view in elevation, largely diagrammatic, and partially in section, of the sweep and sweep actuating mechanism of a standard form of Crawley rounding and 45 backing machine.

Fig. 2 is a detached sectional view showing means employed in accordance with my 50 invention for perfecting the counter-balance.

Fig. 3 is a view in perspective of a book which has been rounded and backed in ac-

cordance with the normal operation of the machine.

The same part is designated by the same reference numeral wherever it occurs throughout the several views.

In the industry for rounding and backing bound books, periodicals, and the like, the machine which is in practical universal use for this purpose is known as the Crawley machine, which is shown and described in detail in United States Letters Patent No. 372,128, dated October 25, 1887, and issued 60 to E. Crawley. For the perfect and satisfactory operation of this machine it is important that the sweep returns quietly to its initial and exact position for new work 65 without rebound or back lash.

Experience has shown that the operating parts for the sweep and sweep jaws soon become worn, due probably to excessive and unnecessary strain on these parts when the sweep is overbalanced as it moves back and forth to perform its designed functions. The result of this wear and looseness of parts is a slam and rebound when the sweep returns, and as a consequence the joints of books are 75 not uniform. To overcome this serious defect it has been proposed to soften the slam by interposing springs to cushion the slam effect. When the parts are worn, however, the spring has a tendency to push or pull, as the case may be, the sweep away from the 80 stop, which is likewise undesirable and detrimental to the satisfactory operation of the machine.

I have found that by applying a counter-weight to the sweep, I am enabled to take up 90 loose motion in all the connected operating parts so that the sweep always returns to the stop in front of the machine, thereby insuring perfect joints and obliterating all slam. It should further be noted, that the counter-weight also takes up excessive and unnecessary strain on the operating parts when the sweep overbalances and, thereby, to a large extent, prevents excessive wear and early deterioration of a rather complicated and expensive machine.

In practicing my invention I have found it feasible and very satisfactory to apply the counterweight to the sweep in the manner clearly indicated by the accompanying drawing, wherein the sweep is represented at 105

and to which is attached by any suitable means, as an eye 11, a flexible or other suitable connection 12, having attached thereto a proper counterweight 13. The flexible connection may pass over a pulley 14 properly supported by a bracket or frame 15.

As is also indicated by the drawing, the size of the joint 16 of the book 17 is controlled by the position of the sweep 10, the sweep jaws 18, the back stop 19, and the sweep adjusting and stop screw 20, which latter may be regulated by an operator's hand-wheel 21 to the proper position for stopping the sweep at desired points for insuring perfect and uniform joints. It is apparent from this arrangement that the sweep will always be definitely positioned when the sweep jaws fasten down on a book in preparation for rounding and backing, as is well understood in the art, and will therefore not be here re-described. It should be noted, however, that the sweep overbalances as it moves away from its initial position, as shown in Fig. 1, for example, and which operation is effected by cam D, through the instrumentalities of the connected cam roller E, the operating toggles K and levers F, and G, which form herein no part of my invention other than for carrying out the same as described above. This overbalancing causes excessive strain and wear on the several connected operating parts, with the result of the slam action heretofore noted, and the inaccurate positioning of the sweep and sweep jaws. The immediate, unexpected, and beneficial results obtained by the application of my invention therefore reside largely in materially reducing wear of the operating parts and in positively and accurately locating the sweep and sweep jaws. In this manner the application of my invention materially prolongs the life

and usefulness of the machine, and at the same time produces more uniform and better joints as has been explained above.

Having now set forth the objects and nature of my invention, and a structure embodying the principles thereof, what I claim as new and useful and of my own invention and desire to secure by Letters Patent is:—

1. In a machine for rounding and backing books, the combination of means for holding the books to be rounded and backed, and a weight flexibly connected to said holding means for preventing back lash of said holding means.

2. In a machine for rounding and backing books, the combination of means for holding the books to be rounded and backed and means for preventing back lash of said holding means, said back lash preventing means comprising a counterweight applied to said holding means.

3. In a machine for rounding and backing books, the combination of a cam-operated sweep and a counterweight attached to said sweep for positively positioning said sweep.

4. In a machine for rounding and backing books, the combination of a cam operated sweep and a counterweight flexibly attached to said sweep to thereby positively influence said sweep in one direction.

5. In a machine for rounding and backing books, a cam operated sweep, a pulley, a flexible connection passing over said pulley, and a weight connected with said sweep by said flexible connection for modifying the movements thereof.

In testimony whereof I have hereunto set my hand on this 4th day of December A. D., 1920.

AXEL VIKTOR JOHNSON.
